UNITED STATES PATENT OFFICE

NEWCOMB K. CHANEY, OF LAKEWOOD, OHIO, ASSIGNOR TO NATIONAL CARBON COMPANY, INC., A CORPORATION OF NEW YORK

REGULATOR FOR SHORT CIRCUIT AMPERAGE ON STARTING ARC LIGHTS

Application filed July 31, 1928. Serial No. 296,458.

This invention relates to electric arc lamps and is especially adaptable for use on the smaller type of such lamps made for burning at the lower amperages permissible on the ordinary lighting circuit.

To permit the safe use of the arc lamp in the home or similar lighting circuit it is necessary to provide sufficient resistance in series with the arc to maintain an amperage within the limits of restriction usually imposed on such a wiring installation. At the same time in order to obtain the most efficient results, especially in a lamp used for therapeutic purposes, it is desirable to operate the arc at the highest possible amperage. Consequently it is customary in construction of lamps for such purposes to provide only enough resistance to maintain the highest permissible amperage when the arc is burning under normal operating conditions, making no provision whatever to take care of the much greater short circuit amperage which is always obtained when striking the arc. Under these conditions the circuit is considerably overloaded when striking and adjusting the arc and since this operation is frequently necessary to insure continuous burning of the arc, especially in the smaller hand operated lamps, danger of blowing the fuses or overheating is often encountered.

The object of my invention is to provide means for regulating this short circuit amperage in such a manner that a lamp may be safely started and operated at the maximum permissible current, and I have accordingly devised a mechanism which may be readily adapted to any type of arc lamp for use under conditions where it is desirable that the starting current not greatly exceed that required for normal operation.

The advantages of this invention will be evident from a description of the accompanying drawing showing one modification as adapted to a parallel trim lamp.

The single figure, partly diagrammatic shows two carbon electrodes 1 and 2 held parallel to one another in suitable holders 3 and 4. Holder 4 is fixed whereas holder 3

and is movable about its point of support 6 by means of the extending lever 7 attached to holder 3. A rod 8 of insulating material having an enlarged end or thumb-piece 9 is mounted in such a manner as to be free to move longitudinally a short distance against the action of a spring 10. Mounted on said rod is a collar 11, and a contact 12 normally held against coacting contact 13 by spring 10. A resistance 14 is in series with the carbon electrodes and is also connected to the contact 12 by a shunt 15.

The arc may be started by pressing inwardly on the thumb piece 9 which in turn causes the collar 11 to exert pressure on the lever 7 and move the tip of electrode 1 toward electrode 2, said electrode 1 and attached lever 7 assuming the position shown by dotted lines. In moving the rod 8 to cause the electrodes to touch each other, the contact 12 is removed from contact 13, also shown by dotted lines, and the circuit is completed from the outside source of current through the line 16, the resistance 14, and two electrodes, and out through the line 17. On releasing the thumb piece 9, the spring 10 causes the rod 8 to move back into its normal position thus bringing together the two contacts 12 and 13 and shunting out the resistance 14, through the shunt 15. At the same time the two electrodes are separated forming an arc.

The resistance 14 is thus effective in lowering the circuit amperage only when the electrodes are touched together to start the arc and until the arc is of approximately the length required for normal operation at which time it is automatically shunted out of the circuit. Another resistance or current limiting means of suitable form, not shown in the drawing, is continually in series circuit with the electrodes and is sufficient with a normal operating arc to maintain a current drain within the permissible range.

Any of the usual forms of electrical resistance may be used for the purpose of lowering the short circuit amperage but I prefer to make such resistance at least equal to or slightly greater than the resistance of the arc of normal length in order that the

amperage on starting the arc will at no time exceed the current drain required for normal operation. If the arc is to be burned only on alternating current a choke coil may be used in place of resistance 14 as a means of limiting the starting amperage and the permanent resistance likewise may be replaced with a choke coil. The contact or switch mechanism may also be of any desired form provided it is so constructed that it will operate to insert additional resistance or other current limiting means in the circuit when striking the arc and shunt out or disconnect the same when the arc has been drawn to the proper operating length.

While I have shown my invention as adapted to a parallel trim lamp it is evident that with slight modifications it may be equally useful on a lamp of any type trim without departing from the spirit of this invention.

I claim:

1. An arc lamp mechanism for regulating the short circuit amperage on starting an arc, comprising in combination a pair of electrodes, an electrical resistance in series circuit with said electrodes, a switch normally maintaining a shunt circuit around said resistance, and means for concomittantly moving the tips of the electrodes together and operating said switch to open said shunt circuit.

2. An arc lamp mechanism for regulating the short circuit amperage on starting an arc, comprising in combination a pair of electrodes, at least one of said electrodes being mounted for movement toward the other, an electrical resistance in series circuit with said electrodes, a switch normally maintaining a shunt circuit around said resistance, and a finger piece manually operable to move said electrodes together and simultaneously operate said switch to open said shunt circuit.

3. An arc lamp comprising electrodes mounted to separate by a predetermined distance and form an arc-gap when released; electrode-moving means operable to shorten the arc-gap; current limiting means in series circuit with the electrodes; a shunt around said current limiting means; and a switch in said shunt to be opened by said electrode-moving-means when the latter is activated to shorten the arc-gap.

4. An arc lamp comprising electrodes mounted to separate by a predetermined distance and form an arc-gap; a resistance in series circuit with said electrodes; a shunt circuit around said resistance; and electrode moving means manually operable to shorten the arc-gap and simultaneously open said shunt circuit.

5. An arc lamp comprising electrodes mounted to separate by a predetermined distance and form an arc-gap when released;

electrode-moving means manually operable to shorten the arc-gap; current limiting means in series circuit with the electrodes; a shunt circuit around said current limiting means; and a switch in said shunt circuit, 70 said switch being connected with said electrode moving means to be opened thereby as the latter is actuated to shorten the arc-gap.

In testimony whereof, I affix my signature.

NEWCOMB K. CHANEY.
